UNITED STATES PATENT OFFICE.

JOHN H. PACKER, OF POCATELLO, IDAHO.

OIL-FILTER.

1,157,717.

Specification of Letters Patent.

Patented Oct. 26, 1915.

Application filed April 3, 1915. Serial No. 18,935.

To all whom it may concern:

Be it known that I, JOHN H. PACKER, a citizen of the United States, residing at Pocatello, in the county of Bannock and State of Idaho, have invented a new and useful Oil-Filter, of which the following is a specification.

The present invention appertains to oil filters, and aims to provide an oil filter having novel means for catching the sediment when the oil enters and flows through the casing of the filter, and also having novel means for straining the oil.

It is also within the scope of the invention to provide an oil filter improved generally in its construction, and which is comparatively simple and inexpensive in construction, as well as being practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in the accompanying drawing, wherein:—

Figure 1 is a vertical section of the filter, taken approximately on the line 1—1 of Fig. 2. Fig. 2 is a horizontal section of the device taken on the line 2—2 of Fig. 1.

In carrying out the invention, there is provided an upright cylindrical casing 1 of suitable size. Secured to and projecting upwardly from the bottom of the casing 1 is an annular sleeve 2 which projects to a point between the upper and lower ends of the casing, and which is arranged adjacent but spaced from the periphery or walls of the casing. A depending annular sleeve 3 is arranged within the sleeve 2 and its lower end terminates adjacent but spaced from the bottom or lower end of the casing, while the upper end of the sleeve or apron 3 is flared or turned outward, as at 4, and secured to the periphery or walls of the casing immediately above the upper end or edge of the sleeve 2. The casing and sleeves are concentric, and the sleeves 2 and 3 are arranged close adjacent one another but are spaced apart. The upper end of the sleeve or apron 3 being secured to the casing sus-

pends the sleeve 3 within the sleeve 2. An annular chamber 5 is provided between the sleeve 2 and casing 1, and an annular chamber 6 is provided between the two sleeves, while a central chamber 7 is provided within the inner sleeve or apron 3.

A downwardly projecting oil inlet pipe 8 is disposed adjacent one side of the casing and has its lower end engaged through the casing adjacent the bottom thereof to communicate with the lower portion of the chamber 5, and the upper end of the inlet or filling pipe 8 is provided with a funnel 9 above the top or upper end of the casing, whereby the waste oil or other oil to be filtered may be readily poured into the pipe 8 to enter the lower portion of the casing.

The bottom of the casing is provided with a drain cock 10 whereby the sediment may be drained from the chambers 6 and 7, and the casing 1 is provided with one or more drain cocks 11 communicating with the lower portion of the chamber 5 for draining the said chamber.

A filtering means 12 is disposed within the casing 1 above the sleeves 2 and 3, and comprises upper and lower circular apertured plates 13 and 14 fitting snugly within the casing 1, and having superposed sheets of suitable fabric or filtering material 15 disposed therebetween. A central clamping bolt 16 is engaged through the plates 13 and 14 and filtering material 15 and bears an upper thumb or wing nut 17 seating upon the plate 15 whereby the plates 13 and 14 may be readily moved toward one another for compressing the filtering material 15 when desired. A nut 18 is threaded upon the bolt 16 and seats against the lower surface of the lower plate 14.

As a means for supporting the straining or filtering means or device 12 within the casing 1, a diametrical bar 19 is terminally secured to the opposite sides of the casing immediately above the sleeve 3, and is provided at its central point with a slot 20. The lower end of the bolt 16 is provided with an elongated head 21 which may be moved downwardly through the slot 20 when the straining or filtering device is inserted into the casing and when the bolt 16 is rotated to the proper position, and the bolt 16 may then be turned for locking the head 21 thereof under the bar 19 for holding the parts in place.

A chamber 22 is provided between the

filtering device 12 and the top or upper end of the casing for holding the filtered oil and the top of the casing is provided with a removable cap 23 which when removed permits access to be had to the nut 17 whereby the said nut may be tightened or loosened for either compressing or loosening the filtering material 15. The casing 1 is also provided with a faucet or other means 24 for drawing off the filtered oil from the chamber 22, and is further provided with a faucet or means 25 for drawing off the air from the upper portions of the chambers 5 and 6 which are in communication. The casing is provided with a glass gage 26 between the filtering device 12 and the upper end of the sleeve 3, and with a second glass gage 27 communicating with the chamber 22.

In operation, the casing is filled with water to a point slightly below the lower plate 14 of the filtering device, the level of the water being indicated by the gage 26. The air may be let out of the chambers 5 and 6, by opening the faucet or valve 25 in order that the water will rise to the desired level within the chambers 5 and 6. The waste or other oil to be filtered is then delivered into the pipe 8 and will flow into the lower portion of the chamber 5 which will tend to catch the sediment therein. The chamber 5 therefore provides a primary sediment basin. The oil may then rise to the upper end of the chamber 5, since the oil is lighter than water, and will be carried downwardly through the chamber 6 into the lower portion of the chamber 7. The chamber 6 serves as a secondary sediment basin, while the chamber 7 provides a third sediment basin, so that the three basins will properly catch the sediment. The oil being carried through the sediment within the respective basins will be given a primary filtering action, and the oil in passing upwardly within the chamber 7 through the filtering device 12 will be finally filtered and strained before it enters the chamber 22. The filtered oil may be drawn off from the chamber 22 through the faucet or valve 24, the level of the filtered oil within the chamber 22 being indicated by the gage 27. It is evident that the plates 13 and 14 of the filtering device may be drawn together for compressing the filtering material 15, whereby the oil will be filtered most effectively and the compressed filtering material 15 in engaging the casing 1 will prevent the oil from escaping around the filtering device.

without passing through the filtering material.

It is preferable to provide the lower end 60 of the sleeve 3 with feet 4^a resting upon or secured to the bottom of the casing, for assisting in supporting the sleeve 3 properly. It is also desirable to provide an annular apertured pipe 9' within the lower portion 65 of the annular chamber 5 to which the lower end of the filling pipe 8 is connected, whereby the oil will enter the pipe 9' from the pipe 8 and will be discharged upwardly within all portions of the chamber 5. 70

The present device may be readily cleaned out by drawing off all of the water from the chamber 5 by opening the valve 11, and then attaching a hose to the valve 10 and opening the said valve 10 whereby the water will 75 pass through the chambers 6 and 5 out through the open valve 11 for cleaning out the sediment from the chambers 5, 6 and 7. The operation may be reversed, for purpose of cleaning out the sediment, by attaching 80 the hose to the valve 11 and opening the valve 10 whereby the sediment will be carried out through the valve 10 with the water. In cleaning out the device, care should be exercised in drawing off as much oil as possible, so as not to waste the oil. The oil can be forced up through the filtering material by forcing water into the chamber 7 so that the water level rises into the filtering material, and the oil will therefore be forced 90 up into the chamber 22 so that it can be readily drawn off before the cleaning operation. 95

Having thus described the invention, what is claimed is:—

In a filter, an upright casing, an upwardly projecting sleeve therein providing a chamber having a lower inlet, a depending sleeve within the aforesaid sleeve and having its upper end outturned and secured to the 100 walls of the casing, a filtering device within the casing above the sleeve and comprising apertured plates fitting within the casing and filtering material between said plates, and clamping means engaged through said 105 plates, the casing having an outlet above the filtering device.

In testimony that I claim the foregoing as my own, I have hereto affixed my signature in the presence of two witnesses.

JOHN H. PACKER.
